219,065

COMBINATION TAPE MEASURE, MAGNIFIER AND LEVEL

Charles Zelnick, Carey, N.C., assignor to Cooper Industries, Inc., Houston, Tex., a corporation of Ohio

Filed June 16, 1969, Ser. No. 17,710

Term of patent 14 years

Int. Cl. D10—08

U.S. Cl. D52—1

Fig. 1

Fig. 5

Fig. 3

Fig. 2

Fig. 4

Fig. 6

FIG. 1 is a perspective view of a combination tape measure, magnifier and level showing my new design; FIG. 2 is a side elevational view thereof;

FIG. 3 is an end elevational view;

FIG. 4 is an opposite end elevational view;

FIG. 5 is a top plan view thereof; and

FIG. 6 is a bottom plan view thereof.

I claim:

The ornamental design for a combination tape measure, magnifier and level, as shown and described.
